UNITED STATES PATENT OFFICE.

WILLIAM SAMUEL COLWELL, OF PITTSBURG, PENNSYLVANIA, AND ANDREW JACKSON DAVIS, OF NEW YORK, ASSIGNORS TO THE TRIPLE THERMIC MOTOR COMPANY, OF NEW YORK, N. Y.

TRIPLE THERMIC MOTOR.

SPECIFICATION forming part of Letters Patent No. 313,183, dated March 3, 1885.

Application filed January 13, 1885. (No model.)

To all whom it may concern:

Be it known that we, WILLIAM SAMUEL COLWELL, of Pittsburg, in the county of Allegheny and State of Pennsylvania, and ANDREW JACKSON DAVIS, of the city and county of New York, in the State of New York, said States being two of the United States of America, have invented a new and useful Improvement on Triple Thermic Motors or Bisulphide-of-Carbon Engines; and we do hereby declare that the following is a full, clear, and exact description thereof, reference being had to the accompanying drawings, and to the letters of reference marked thereon.

The object of our improvement is the utilization of specific, latent, and sensible heat in generating a motor by evolving vapor from bisulphide of carbon for operating engines. Engineers of reputed scientific skill assert that "the capacity of a body for heat is termed 'its specific heat,' and may be defined as the number of units of heat necessary to raise the temperature of one pound of that body to 1° Fahrenheit." "The thermal unit, or 'unit of heat,' as it is termed, is the quantity of heat that will raise one pound of pure water 1° Fahrenheit, or from 39° to 40° Fahrenheit." "The term 'latent heat' means the quantity of heat which has disappeared from a body, owing to an increase of temperature. The 'sensible heat' is that which is sensible to the touch or measurable by the thermometer." "The mechanical equivalent of heat is the amount of work performed by the conversion of one unit of heat into work, and the mechanical theory of heat is based on the assumption that heat and work are mutually convertible." Prof. Tyndall's definition of specific, latent, and sensible heat, briefly restated, is that atoms unite and form molecules, molecules unite and form masses. Specific heat is the heat required to cause the atoms to revolve on their axes, or when united in molecules to revolve around each other. Latent heat, as regards steam, is the heat that is consumed in pulling the liquid molecules asunder, forming vapor. When the heat is withdrawn, the vapor condenses, and precisely the same quantity of heat reappears and becomes sensible,

which is the heat that is expressed by degrees of temperature as indicated by the thermometer. These definitions of specific, latent, and sensible heat are given for the purpose of enabling the skillful engineer to clearly understand the object, nature, and principle of operation of our invention, which consists in the method hereinafter described for generating a motor from bisulphide of carbon by evolving a vapor therefrom with the least possible loss of units of heat in operating an engine and economizing fuel.

To enable others skilled in the art with which our invention is most nearly connected to make and use the same, we will proceed to describe it and the operation thereof.

In the accompanying drawings, which form part of this specification, Figure 1 is a side elevation of one form of apparatus or engine we employ for generating a motor from bisulphide of carbon. Fig. 2 is a vertical longitudinal section of a boiler employed for evolving bisulphide of carbon into a vapor for a motor, enlarged view. Fig. 3 is a vertical and transverse section of said boiler at line 1 of Fig. 2, enlarged view. Fig. 4 is a vertical and transverse section of said boiler at line 2 of Fig. 2, enlarged view. Fig. 5 is a vertical and transverse section of said boiler at line 3 of Fig. 2, enlarged view. Fig. 6 is a top or plan of the angle-iron end flanges. Fig. 7 is a top or plan of said flanges when arranged in juxtaposition. Fig. 8 is a vertical section of the regulating-valve for controlling the flow of steam into and around the boiler for evolving the bisulphide into a vapor, enlarged view. Fig. 9 is a vertical section of the regulating-valve for controlling the admission of steam into the casing around the vapor-conduit which conveys it to the cylinder of the engine, and into the casing surrounding the said cylinder, for expanding and maintaining the heat of said vapor, enlarged view. Fig. 10 is a vertical section of the washer, enlarged view. Fig. 11 is a vertical section of the cylinder-head and packing mechanism for the piston and valve rods. Fig. 12 represents a side elevation of the heater, enlarged view, showing

a part of the shell broken away for the purpose of representing the heating-coil within said shell.

In the operation of the engine hereinafter described we desire to impress upon the mind of the constructor and operator that the engine does not exhaust the vapor into the atmosphere, nor does any of the vapor escape into the engine-room, as in the case of the ordinary engine, the peculiar construction of the several parts being such as to preclude all possible escape of vapor.

Another very important feature connected with the use of liquid bisulphide of carbon and the vapor evolved therefrom, is that in its frequent passage from the generator through the engine and condensers, and its return again to the generator, the liquid bisulphide out of carbon is purified and freed from the sulphurated hydrogen, which is always present in the bisulphide of carbon of commerce.

Experience in operating the engine herein-after described with the vapor of bisulphide of carbon as a motor has demonstrated the fact that two or three days' working of said vapor will render the liquid bisulphide nearly inodorous, and the noxious and pungent smell common to bisulphide of carbon will be destroyed. Samples of the liquid bisulphide, after having been worked several days, have been drawn from the generator and submitted to manufacturers of liquid bisulphide and to chemists, and they were unable to tell that it was liquid bisulphide of carbon by the senses of sight and smell.

Having stated the foregoing facts, we will proceed to describe the construction and operation of the engine and the several parts connected therewith.

Reference being had to the accompanying drawings, A represents an ordinary steam-boiler, which may be provided with the usual appendages common to such boilers.

The vapor-generator B is shown in longitudinal vertical section in Fig. 2, and in transverse vertical section in Figs. 3, 4, and 5, in which a represents the casing which surrounds the shell b of the boiler c, which is furnished with a large number of tubes, d, extending through the boiler, and secured in the ends thereof in the usual way. The head e of one end of the boiler extends beyond the diameter of the shell b sufficiently to form a suitable bearing or flange for attaching it to the flange f of the casing a, to which is also attached the flange of the part l, which forms a circulating-chamber, g.

On one end and each side of the outer wall of the shell b of the boiler c are secured flanges f, which are attached to and rest upon similar flanges on the inner side walls and one end of the casing a, which flanges are so attached to each other as to form a steam-tight joint. In the boiler c, above its tubes d, is arranged a perforated pipe, i, extending longitudinally from end to end of said boiler, and communi-

cates with the vapor-conducting pipe B', which pipe passes through the casing a and the shell b of the boiler c. In the upper side of pipe i are a large number of perforations, and in the lower side a smaller number, the latter perforations being employed for draining said pipe of the liquid resulting from the condensation of the vapor. The pipe i is used for the purpose of drawing off the vapor evenly and uniformly from the upper compartment of the boiler.

On the under side of the boiler c, in the space j formed by the casing a, is arranged a perforated pipe, k, which communicates with steam-supply pipe A', and is employed for the distribution of steam around the lower half of the shell b of the boiler c, the steam being confined around the lower half of the boiler by the flanges f, and caused to flow through the tubes d into the distributing or circulating chamber g, from which it flows back through the tubes d, above the flanges f, and surrounds the upper half of the boiler, the course of the steam being indicated by arrows. The bonnet l and the end m are stayed through the medium of rods n, which pass through the tubes d and through said bonnet and end m, and are secured thereto by screw-nuts, as shown. The casing a is surrounded by a suitable non-conducting covering. The pipe B'

communicates with the vapor-chest of the cylinder of the engine C, and is surrounded with a casing, C', which is supplied with live steam directly from the steam-boiler A, and automatically controlled by a regulating-valve, F',

which casing C' also communicates with the casing which surrounds the vapor chest and cylinder of the engine C, which is of ordinary construction and operation. By this construction and arrangement of the boiler c, casing a, chamber g, and pipes i, k, and A', the steam is distributed thoroughly over the entire surface of the shell b, and caused to travel through the tubes d in one direction in the lower half of the boiler c and in an opposite direction

through the tubes d, located above the flanges f, the steam acting first on the lower half of the shell of the boiler c, heating it, then passing through tubes d in that part, heating them, and then passing into chamber g, and from it

entering the tubes d, above the flanges f, heating them, and, passing from them, enters the upper half of the steam-space, spreading over the upper surface of the shell b, heating it, so that the bisulphide of carbon evolved into

vapor in the lower part of the boiler c is super-heated in the upper part of it, and enters the pipe B', which, being surrounded by the casing C', and which communicates with the casing around the cylinder and vapor-chest of the engine C, and supplied with live steam from the boiler A through pipe o, the bisulphide-of-carbon vapor evolved in the boiler c is continuously heated by said live steam until it has performed its office upon the piston

of the engine C. The steam from boiler A, passing through pipe A', enters the regulat-

ing-valve L M, passing from it through pipe Q' to pipe k into the lower part of the casing a, and is distributed as hereinbefore described, the quantity and pressure of steam in the casing a being controlled by the regulating-valve L M, so that any desired pressure of bisulphide-of-carbon vapor may be obtained by the proper adjustment of said valve.

In practice we have found that a pressure of about eight pounds per square inch of boiler-surface is sufficient to evolve a vapor of about seventy pounds pressure per square inch of boiler-surface, and that forty-five pounds pressure per square inch of boiler-surface in the steam-boiler A, being conveyed through pipe o into the casing C', will superheat the vapor and increase the tension and pressure thereof after it leaves the vapor generator or boiler c. The casing C' around the vapor-conduit B', and the casing around the cylinder and vapor-chest of the engine C, are also provided with suitable non-conducting coverings.

The flanges of angle-iron represented in Figs. 6 and 7 are secured one to the inner end 25 wall of the casing a, the other to the end of the boiler c, about the horizontal center of said boiler and casing, the one resting upon the other, as shown in Fig. 7, forming the side and one end partitions between the lower and 30 upper part of the casing, as shown in Figs. 3, 4, and 5, with suitable openings in the end partition for the heating-coil p, which communicates with the coil q in the heater D, which communicates with the pump H, which 35 communicates with the well G. The lower end of the heater D communicates with the exhaust of the engine C through the medium of pipe D', which is provided with a stop-valve, P, which is employed for the purpose of cutting 40 off the engine C from communication with the condensers E and F, thereby preventing the vacuum formed in the condensers and well G from being destroyed while adjusting or 45 repairing any part of the engine C. The upper end of the heater D communicates with the condenser E through the medium of pipe T, and the condenser E communicates with the auxiliary condenser F through the medium of 50 pipe U, and the auxiliary condenser F communicates with the vacuum-pump I through the medium of pipe V, and with the well G through the medium of pipe W, and the well G communicates with the pump H through the medium of pipe X, and pump H communicates with the 55 heating-coil in heater D through the medium of pipe Y, which coil is heated by the exhaust-vapor from the engine, and the heating-coil q in heater D by pipe Q communicates with the coil p in the casing a, where the liquid bisulphide is further heated by the steam in casing a before entering the boiler c, and said coil communicates with the boiler c, thereby returning the liquid bisulphide into said boiler at or about its boiling-point. The condensers 60 F and E are supplied with water through the medium of pipe E', the water flowing into the

auxiliary condenser F, and from it through pipe U into condenser E, and the overflow passing off through the medium of pipe K'. The condensed bisulphide of carbon flows from 70 the condenser E through pipe G' to the vacuum-pump I, which also draws off the air and uncondensed vapors from the condenser, and discharges said liquid, air, and vapors through pipe V into the auxiliary condenser F, from 75 which they flow through pipe W into the well G. The uncondensed vapors, gases, and air contained in the well G pass up through pipe H', having check-valve t, and down into and below the surface of the water contained in the 80 washer K, which is provided with a water-overflow pipe, I', connected to the water-overflow pipe K' of the condenser E, by which, in conjunction with the vacuum-pump I, a vacuum is provided in the washer above the water, and causes the uncondensed vapors and air to rise from the well G. Said washer is also provided with a water-supply pipe, J', which communicates with the water-supply pipe E. The condensable vapors and gases 85 are condensed through the medium of the water in the washer K, the liquid bisulphide of carbon purified and precipitated into the bottom of the heater, and withdrawn at suitable intervals through the pipe r, and returned into 90 the well G, while the incondensable gases and washed air pass off through the pipe I' into the overflow-pipe K', by which they are carried to any suitable point.

The washer K is provided with a sight-gage, 100 L', for indicating the height of the water in said washer.

The petcocks s s, when open, communicate with the drain-pipe M', which communicates with the casing around the cylinder and with 105 the steam-trap R', and the steam-trap R' communicates, through the medium of pipe u, with the pipe O', which communicates with the boiler-feed pump J, whereby the water of condensation in the casing C' and casing of 110 the cylinder is conveyed to the pump J.

The pipe N' communicates with the casing a of the bisulphide-boiler c and with the pipe O', whereby the water of condensation is conveyed from the casing a to the pump J, thus returning 115 all of said water of condensation to the steam-boiler A at about the boiling-point.

To the steam-pipe A' is attached a pipe, v, for supplying the pump J with steam, and the exhaust-steam of said pump is conducted 120 through pipe w into the pipe Q', which conveys steam at a pressure lower than the boiler-pressure into the casing a which surrounds the bisulphide-boiler c.

The pipe x, connected with the steam-pipe 125 A', conducts steam to the vacuum-pump I, and its steam is exhausted through pipe a' into the pipe Q'.

The pipe y, connected to the steam-pipe A', conducts steam to the pump H, and its steam 130 is exhausted through pipe b' into the pipe Q'.

By exhausting the steam from the several

pumps as described, the heat of said exhaust-steam is utilized, in conjunction with the steam directly from the steam-boiler A, to evolve vapor from the liquid bisulphide of carbon in the boiler c.

To the valve-casing of the valve P in the exhaust-pipe D' is attached a pipe, T', having a U trap S', which pipe communicates with the pipe G'. By this arrangement the liquid bisulphide of carbon resulting from condensation in the exhaust-pipe D' and in the casing of the valve P is conveyed to the vacuum-pump I, and discharged through the pipe V into the auxiliary condenser F, from which it is discharged into the well G.

To relieve the vapor-generator of air, preparatory to admitting steam to evolve vapor, pipes y'' are provided, which communicate with the space between the casing a and vapor-boiler c. Above the horizontal partition therein said pipes terminate in one pipe, which passes through the outer casing, and is provided with a suitable valve for controlling the flow of the air. Said pipe may be connected with the overflow-pipe from the condenser E or discharge into the open air.

The bisulphide-of-carbon boiler or generator is provided with a safety-valve, U', of ordinary construction, which communicates with the vapor-conduit B' through the medium of the pipe X' and with the condenser E through the medium of pipe V'. This valve is employed to carry off any excess of pressure of the vapor in the boiler c, and to conduct it to the condenser.

The regulating-valve L M (see Fig. 8) consists of two chambers, c' d', which are secured together with a non-conducting packing, e', placed between them—such as asbestos. The chamber c' is provided with a plunger, h', connected to a pivoted lever, f', having an adjustable weight, g'. The lower end of the plunger h' is of the form of a section of a sphere, which prevents it from cutting or otherwise injuring the elastic diaphragm n', which divides the chamber c' into two compartments. The chamber d' is furnished with a balance-valve, i', and seats for it. The stem j' of said valve is connected to the lever f'.

To the chamber d' is attached a pipe, A', which communicates with the steam-boiler A.

To the chamber c' is connected a pipe, q', which communicates with the boiler c, and is provided with a valve, l', above which the pipe q' is filled with water. The weight g' being adjusted on lever f' for the desired working-pressure of vapor of the bisulphide of carbon in the boiler c. Steam from boiler A, flowing through pipe A', enters the chamber d' of the regulating-valve L M, passes therefrom through the pipe Q' to the boiler c. The vapor of bisulphide of carbon passes from boiler c, filling the pipe m', in which it condenses, until it fills the pipe in U-shaped bend of said pipe to about the dotted line x. The valve l' now being opened, the vapor of bisulphide of

carbon presses against the liquid bisulphide of carbon, which, acting on the water, and it against the diaphragm y', and it against the plunger h', which, in combination with lever f' and weight g', will open and close the valve in accordance with the pressure of the vapor of bisulphide of carbon in the boiler c; said valve closing when the pressure is greater than that fixed upon, and opening when it is less, thereby diminishing the flow of steam through pipe Q' when the pressure of bisulphide-of-carbon vapor is greater than that determined upon and increasing said flow when it is less, thus increasing or diminishing heat around and through the liquid bisulphide of carbon in boiler c, whereby the desired working-pressure of the vapor of bisulphide of carbon is always maintained.

The supply and regulating valve F' is constructed in all respects the same as the regulating-valve L M, excepting the pipes s' t', the latter of which communicates with the casing C' surrounding the conduit B', leading to the cylinder of the engine, and the operation of valve F' is the same as the valve L M, excepting that the steam which enters it also operates the valve and plunger for controlling the admission of said steam into the casing C'. The pipe o, attached to the valve F', communicates with the steam-boiler A. Now, by adjusting the weight o' on the lever p', for obtaining the pressure of steam desired in the casing C', which may be indicated by the gage, the operation will be as follows: The steam flowing from the steam-boiler A through pipe o enters the chamber r', and from it, through pipe t', enters casing C', which communicates with the casing around the cylinder of the engine C, so that the same pressure of steam which is in the casing C' will also be in the casing of the cylinder. In the event of the pressure in the boiler A increasing beyond that determined upon in the casing C', the pressure of steam will act against the diaphragm u', which, acting against the plunger v', will thereby, through the medium of lever p', close the valve w', so as to cut off or partly cut off the steam until the desired pressure is attained in the case C' and the casing of the cylinder of the engine C. If the pressure in said casings should become less than that desired, then the weight o', through the medium of the lever p', will open the valve w', so as to admit more steam, and will hold the valve open till the desired pressure is attained. It will be observed that by this arrangement of the supply and regulating valve F' with relation to the casing C', and it communicating with the casing of the cylinder of the engine C, uniform pressure may be maintained in said casings, notwithstanding any variation of pressure that may occur in the boiler A, and that the pressure in said casings is greater than that in the casing a around boiler c.

The various and several pipes hereinbefore described are provided with suitable valves

for controlling the flow of the liquids, fluids, and gases which flow through the said pipes. The well G is provided with the usual sight-gage, and the casing a, the vapor-boiler c, the steam-pipe A', and casing C' are provided with pressure-gages for indicating the pressure in said parts.

The piston and valve rods are packed as follows, (see Fig. 11, in which a" is the piston-rod, b" is the cylinder-head, having packing-caps c" d", packing-glands e" f", and ring g", having recesses h" i", which communicate with each other by a series of openings:) In the projection j" of the cylinder-head is a chamber in which is placed plumbago packing, the ring g", then plumbago packing, which is followed by the gland f", which is provided with a chamber, k", for oil, and a recess, l", for the reception of plumbago packing, which is followed by the packing-gland e". The glands e" f" are forced against the packing by means of the screw-caps c" d". The oil-cup m" communicates with the chamber k" in the gland f" by means of a pipe, u", having a valve, o", whereby the rod is surrounded with oil. The projection j" of the cylinder-head b" is provided with a pipe, p", which communicates with the exhaust-pipe D' of the engine, as shown in Fig. 1, which is connected to the vacuum-pump J, whereby the escaping vapors from around the rods are conducted to the vacuum-pump and eventually into the well G.

The lubricating device for the engine consists of pipe r", which communicates with the valve-chest and cylinder of said engine and the conduit B', said pipe having valves s".

To the pipe r" is attached a vessel communicating with said pipe at a point between the valves s". The operator charges into the vessel q" pulverized plumbago, (which is the only lubricant used in connection with the engine cylinder and valve,) and then opens the valves s", and the vapor from the conduit B' forces the plumbago into the valve-chest and cylinder, lubricating the valve and the piston.

The engine may be supplied with cut-off mechanism common to steam-engines.

The operation of our invention is as follows: Steam generated in boiler A is conducted through pipe A'. Passing through pressure-reducing valve L M, it is conveyed into the casing a by pipe Q', and distributed by pipe k around the bisulphide-of-carbon-vapor boiler c at a pressure (and consequently a temperature) greatly below that of the steam in the boiler A, and evolves vapor from said liquid bisulphide of carbon, which vapor as it rises in the boiler is superheated in the upper part thereof, and conducted through a conduit, B', to the engine, the vapor conduit, cylinder, and valve-chest being provided with casings supplied with steam from the boiler under greater pressure (and consequently at a higher temperature) than the steam which evolved the vapor, it (the vapor) has its tension increased, and is maintained at such increased ten-

sion until it has performed its office upon the piston of the engine. The exhaust-vapor is conducted from the engine through the heater D, imparting its heat to the liquid bisulphide of carbon on its way to the boiler from the pump H, while at the same time the temperature of the exhaust-vapor is being reduced by contact with the coil of pipe through which the liquid bisulphide is passing on its way to the boiler, in which it is again evolved into vapor. From the heater D the vapor passes on to the condenser E, in which it passes around a series of tubes through which cold water is kept in constant circulation. From the condenser E the liquid bisulphide, the condensed vapor or gas, and air are drawn by the vacuum-pump I, and thereby conducted into the auxiliary condenser F, where further condensation is effected in like manner. The liquid bisulphide then passes from the condenser F into the well G, the uncondensed vapor, gas, and the air passing from the well G into the washer H, where they are passed through a body of water, condensing the remaining condensable vapor, and relieving the air and incondensable gases of their noxious odors, after which they pass through a pipe to the overflow-pipe leading from the condenser E. The liquid bisulphide of carbon precipitated in the bottom of the washer, being withdrawn at suitable intervals and passed into the well G, is also returned to the boiler c, to be worked over and over again. From the heater D the liquid bisulphide of carbon is conducted through pipe Q into and through a coil located in one end of the casing a, where it is subjected to the heat of the steam in said casing before it is delivered into the body of the liquid in the boiler c, thus greatly increasing the temperature and facilitating its evolution into vapor in said boiler c.

By the steps above enumerated it will be observed that upon starting the engine the liquid bisulphide of carbon is first subjected to heat in the boiler c of comparatively low temperature, to evolve vapor, and the vapor subjected to a higher temperature, to superheat it and consequently increase its tension, which increased tension is maintained throughout the time the vapor is performing work in the engine. After the vapor has passed through the engine and condenser the steps in the operation of evolving the vapor are changed. The liquid bisulphide of carbon is drawn from the well G by the pump H, and forced through the coil q in the heater D, where it is heated by the hot vapors from the exhaust of the engine surrounding the coil in the heater through which said liquid bisulphide of carbon is passing. After leaving the coil in the heater D the liquid is conducted into and through the coil p in the end of the casing a, where its temperature is still further increased by the heat of the steam in said casing, and enters the bisulphide-boiler c at its boiling-point. In the lower part of the boiler the liquid bisulphide

of carbon is evolved into vapor, and the vapor is superheated in the upper part of said boiler *c* by the steam in the casing *a*, and after leaving the boiler *c* the vapor is still further superheated by live steam at a higher degree of pressure (and consequent temperature) drawn directly from the steam-boiler *A*.

The supply of steam from the steam-boiler to the vapor-generator may be cut off at will by means of the stop-valve *R*, between said boiler and the pressure-regulating valve *L M*.

By the construction and arrangement of the automatic pressure-regulating valves which control the supply of steam from the steam-boiler *A* to the vapor-generating boiler *c* and to the casing *C'*, the pressure of the vapor evolved in the generator, and the tension of the vapor in the conduit *B'*, will be kept at a predetermined height. Should the pressure in the vapor-generator increase above that required, from any cause (such as the reduction of the work required to be done by the engine) the excess of vapor will immediately open the safety-valve *U'* and flow through pipe *V'* to the condenser *E*, thus avoiding any danger from said excess of vapor in the boiler *c*, while at the same time the supply of steam to the vapor-boiler and to the casing *C'* around the vapor-conduit will be cut off until the pressure is reduced in both to the desired amount. All of the pumps are supplied with steam from the main steam-supply pipe *A'*, and the exhaust therefrom is returned to the pipe *Q'*, which conducts steam at a reduced pressure to the casing *a*, surrounding the vapor-boiler *c*.

By connecting the chambers in the packing-boxes around the piston and valve rod and the cylinder petcocks with the exhaust-pipe and vacuum-pump all possibility of escape of vapor is absolutely obviated. All of the water resulting from the condensation of steam applied to evolve the liquid bisulphide of carbon into vapor and to superheat the said vapor is returned by pump *J* to the steam-boiler *A* at nearly its boiling-point.

The various methods involved and the means employed in generating a motor, and the construction of the packing-boxes for the piston and valve rods of the engine are not herein claimed, broadly, as they constitute subjects-matter of claims in the applications of William S. Colwell, numbered, respect-

ively, 138,819, 140,111, 140,969, and 141,109, filed July 26, August 9, August 19, and August 21, 1884, but only so much of the means as are specifically set forth in our claims. 55

Having thus fully described our invention, what we claim is—

1. In a bisulphide-of-carbon engine, the combination of a steam-boiler, a vapor-generator, a main and an auxiliary condenser, and a well to collect the liquid bisulphide of carbon resulting from condensation of the exhaust-vapors from the engine, substantially as 65 described.

2. In a bisulphide-of-carbon engine, the combination of a steam-boiler, a vapor-generator, a main and an auxiliary condenser, a supply-pipe conducting water to the auxiliary 70 condenser, from which it passes to the main condenser, a water-overflow pipe, and a well, substantially as described.

3. In a bisulphide-of-carbon engine, the combination of a steam-boiler, a vapor-generator, a heater, a main and auxiliary condenser, a well, and a vacuum-pump, substantially as described. 75

4. In a bisulphide-of-carbon engine, the combination of a steam-boiler, a vapor-generator, a heater, a main and auxiliary condenser, a well, a washer, and a vacuum-pump, substantially as described. 80

5. In a bisulphide-of-carbon engine, the combination of a steam-boiler, a vapor-generator, a heater, a main and auxiliary condenser, a well, a vacuum-pump, and a pump 85 for returning the liquid bisulphide of carbon to the vapor-generator, substantially as described. 90

6. In a bisulphide-of-carbon generator, a pipe communicating with the space between the inner and outer vessels, and adapted by means of suitable connections to relieve the generator of air preparatory to introducing 95 steam to evolve vapor, substantially as described.

WILLIAM SAMUEL COLWELL.
ANDREW JACKSON DAVIS.

Witnesses for William Samuel Colwell:

JAMES J. JOHNSTON,
FRED W. HAAS.

Witnesses for Andrew Jackson Davis:

THOMAS W. KNIGHT,
EDWIN E. WISE.
